Murray B. Boyer
ATTORNEY.

UNITED STATES PATENT OFFICE

GEORGE W. BORTON, OF NEW LISBON, NEW JERSEY, ASSIGNOR TO PENNSYLVANIA CRUSHER COMPANY, OF NEW YORK, N. Y., A CORPORATION OF NEW YORK

FRAME FOR CRUSHING MACHINERY

Application filed May 8, 1924. Serial No. 711,786.

My invention relates to the construction of that type of crushing machinery known as a single-roll crusher, designed and employed for the purpose of reducing mineral bodies such as coal, ore and the like, to convenient size, and the main object of my invention is to simplify and cheapen the construction of the frames of single-roll crushers.

10 A further object of my invention is to provide a frame which shall be massive in character, of maximum strength and particularly adapted for sustaining the stresses and strains incident to the use of structures such as single-roll crushers.

15 And a further object of my invention is to utilize sections of heavy commercial rolled metal members of I-beam section for the sides of such frame whereby I am enabled to take 20 full advantage of the inherent stiffness and rigidity presented by the integral web and flanges of such members or sections.

25 My improved crusher frame is of the built-up type, that is to say, it is made of structural metal in substantially rectangular form, and its side walls comprise a pair of I-beam members, which are connected together and spaced apart by suitable sections or members of rolled metal. The lower part of the web and 30 the base flanges of said I-beam sections are continuous throughout their length, while portions of the top flanges and a portion of the upper part of the central webs are cut out midway the ends of such I-beams for the 35 insertion of the crusher roll shaft bearings; the cut-out portions being filled in with matching parts, detachably secured in place, to complete the side walls of the frame.

These and other features of my invention 40 are more fully described hereinafter; reference being had to the accompanying drawings, in which:

45 Figure 1, is a perspective view of a crusher frame having side walls of I-beam section, within the scope of my invention.

Fig. 2, is a side elevation on a smaller scale, of my improved structure, and

Fig. 3, is a cross sectional view on the line III—III, Fig. 2.

50 In the drawings, 1, 1, represent the sides of

the crusher frame, made of structural shapes, preferably I-beam sections, each side having a web 2, with upper integral flanges 3 and 3^a, and lower integral flanges 4 and 4^a. These sides are connected together, top and bottom, at their respective ends by cross members or plates, those at one end of the frame for instance comprising a top plate 5, secured to the flanges 3 and 3^a, by rivets 5^a, and spacing the top portion of the sides, and a bottom plate 6, connected to the lower flanges 4 and 4^a by rivets 6^a, and spacing the lower portion of the sides. The plate 5 is provided with an inclined portion 5^b which fits between the webs 2 of the I-beams, below the top of the same; such inclined portion 5^b of the plate 5 serving to direct the material to the crushing roll, (indicated by broken lines), and the upper flanges 3^a of the I-beams being cut away, as clearly illustrated in the drawings, to permit this arrangement and to accommodate the crushing roll.

At the opposite end of the frame, the I-beam sides are connected together by a top plate 7, which may be secured to the flanges 3, by rivets 7^a, and a bottom plate 8, which may be secured to the flanges 4, by rivets 8^a. In addition, angle sections 10, vertically disposed, are secured to the webs 2 of the I-beams at the ends of the same externally of said sides, by means of rivets 10^a, and cross-braces 11, 12 and 13, extend across the end of the frame between these vertical angle members 10; such cross-braces being secured to said members 10 by rivets or other suitable means. The cross-brace 11, underlying the plate 7, may be an angle member secured by rivets 11^a, to said top plate and to the vertical members 10; the cross-brace 13 may be in the form of a channel member secured by rivets 13^a or otherwise fastened to the bottom cross plate 8 and to the vertical angle members 10, and the cross-brace 12, which is in the form of an angle member, may be secured to the vertical members 10 and also to the top flange of the channel member 13, by rivets 12^a, or other suitable fastening means.

The top flange 3^a of each I-beam section forming the sides of the frame is cut away midway its ends, as indicated at 15, for re-

ception of the inclined portion 5^b of the plate 5 and the crushing roll; the position of which latter element is indicated in the drawing by broken lines, and in addition, the webs of the I-beam sides are notched or cut away at 16, 5 for the reception of journal-boxes 20, receiving bearings 21, for the shaft of the crushing roll. The gaps in the webs of the I-beam side plates receive filler plates 22, whose lower edge is preferably curved to fit over the journal-boxes, and superposed upon these plates are flanged sections 23, which may be of cast metal, to fill out the gaps in the I-beam sides, with flanges 23^a flush with the upper surface of and continuous with the flanges 3 of the I-beam sections 1.

A cross-brace 24 of I-beam construction is disposed between the sides 1, 1, of the frame; the top and bottom flanges of the cross-brace being cut away at the ends of the same so that the edge of the web of such beam may fit against the web of the beams forming the sides, and the top and bottom flanges of the same. This cross-brace may be secured by bolts, rivets or the like, passing through the upper and lower flanges of the same and through the top and bottom plates 5 and 5^a; the upper rivets being indicated at 5^a. Angle members 24^a are secured at the ends of the cross-brace where they abut the side frames; such angle members being also secured to said side frames by rivets, bolts or other suitable fastening means.

In addition to the journal-boxes to receive the shaft of the crushing roll, the ends of the I-beam sides opposite the cross-braces 11, 12 and 13, are provided with boxes 25, which may be secured to the webs 2 by rivets 25^a; such boxes receiving the bearings for the driving shaft, indicated by dotted lines. The webs of the I-beams are also apertured at 28, for the passage of the shaft or spindle upon which the concave or breaker plate of unitary or sectional construction (not shown), is hung.

By my improved construction I take advantage of the massive character of the I-beam members and the strength and rigidity of the same provided by the integral web and flanges which afford the necessary support for the cross-braces and other elements which make up the complete structure and maintain the parts in spaced relation.

As may be understood, the necessary rivet holes can be punched in proper position by the use of templates and the whole structure fabricated in a cheaper and simpler manner than structures of the type in which side plates of cast metal are employed, with the added advantage that no part of the structure subject to breaking stress or strain is of cast metal.

I claim:

1. A frame for single roll crushers of massive construction, comprising side walls of

standard rolled metal I-beams; said walls being notched intermediate their ends by cutting through the upper flanges and web of said I-beams for the reception of journal-boxes; filler members closing the gaps in said walls and having portions conforming exactly to the web and flange of said side walls, and means for securing said parts together including cross members of standard rolled sections.

2. In a frame for single roll crushers of massive construction, the combination of side plates made of standard rolled I-beam sections; the web of said plates being notched for the reception of journal-boxes, cast metal supports for said journal-boxes conforming to the flange and web of said I-beam side plates, filler members closing the gap in said side plates, means for detachably securing said filler members in place, and independent journal-boxes detachably carried by said I-beam webs for the reception of a driving shaft.

3. A frame for crushing machinery of massive construction, comprising side plates of standard rolled I-beams, cross members connecting the web and flanges of said I-beam side plates and comprising standard sections of rolled metal; said side plates having their upper flanges and web cut away intermediate their ends, cast metal journal boxes having detachable portions adapted to said recessed portions of the side plates, means for connecting the lower portions of said journal boxes to the web and lower flanges of said side plates, and filler blocks conforming to the cut away portions of said side plates overlying the detachable portions of said journal boxes.

4. A side frame construction for massive single roll crushers, comprising an integral member substantially U-shape in contour by reason of a recess intermediate the end portions of the same; said side frame consisting of a section of standard rolled structural metal comprising a web and upper and lower flanges and said recess having substantially vertical walls, a filling member engaging said side walls and closing said recess longitudinally of said side frame; said filling member lying flush with the upper surface of the side frame, and means for securing said side frame and filling member in rigid relationship.

5. A side frame construction for massive single roll crushers, comprising an integral member substantially U-shape in contour by reason of a recess intermediate the end portions of the same; said side frame consisting of a section of standard rolled structural metal comprising a central web and upper and lower flanges and said recess having vertical walls, a filling member engaging said side walls and closing said recess longitudinally of said side frame; said filling member

having a portion lying flush with the inner surface of the web portions and overlying said web adjacent the walls of the recess and a portion flush with the upper surface of the end portions of the side frame, and means for securing said filling member and side frame in rigid relationship.

5 In witness whereof I have signed this specification.

GEORGE W. BORTON.
